UNITED STATES PATENT OFFICE

ARY KAUFMANN, OF SOUTH ORANGE, NEW JERSEY

DESIGN FOR A TRIMMED BAG-FRAME BAND

Application filed May 11, 1931. Serial No. 39,804. Term of patent 3½ years.

To all whom it may concern:

Be it known that I, ARY KAUFMANN, a citizen of the United States, residing at South Orange, in the county of Essex and State of New Jersey, have invented a new, original, and ornamental Design for Trimmed Bag-Frame Band, of which the following is a specification, reference being had to the accompanying drawings, forming part thereof.

In said drawings, Fig. 1 is a perspective view and Fig. 2 is a top plan view of a

trimmed bag-frame band showing my new design.

An important feature of the invention resides in the provision of trimming elements certain of the surfaces of which have a color or tone in contract to the color or tone of adjacent surfaces, thereby providing the design in a two-tone color effect.

I claim:

The ornamental design for a trimmed bag-frame band, as shown and described.

ARY KAUFMANN.
